Application October 2, 1936, Serial No. 103,640

18 Claims. (Cl. 139—55)

This invention relates to control apparatus used for controlling the operation of a machine having a plurality of parts to be selectively actuated, an example of such a machine being a loom for the weaving of figured fabrics in which the warp threads are manipulated by the heddles in accordance with a pattern to produce the desired design on the fabric. More particularly, the invention is concerned with a novel apparatus of the electro-mechanical type which may be employed for both selecting and operating the parts requiring selective actuation. While the invention may be employed in connection with the machines of various sorts, it affords special advantages when employed in connection with a loom, and an embodiment of the invention for that particular purpose will, accordingly, be illustrated and described in detail for purposes of explanation, although it is to be understood that the utility of the invention is not limited to that specific adaptation.

When used for controlling the operation of a loom, the new device makes use of a pattern sheet carrying a representation of the design to be reproduced and it includes devices for operating the heddles selectively, these devices being controlled by mechanism which scans the pattern sheet. The apparatus thus takes the place of a Jacquard mechanism and obviates the necessity of preparing a set of punched cards for each type of fabric to be woven. The use of the new apparatus consequently simplifies and reduces the cost of manufacturing patterned fabrics to an important extent.

The principles of the invention may be employed in various types of apparatus, but in all forms, the mechanism includes selectively operated control members which are connected to the parts to be controlled and actuating means cooperating with the control members to cause actuation of the selected parts. When the apparatus is used on a loom, the pattern control mechanism includes a plurality of control and operating devices, one for each heddle or group of heddles to be actuated in unison, and each such device includes a control member connected directly to the heddle or group of heddles. The control members are selected by selector elements, one for each control member, these selector elements being selectively operated under the control of mechanism scanning the pattern sheet. In one form of the apparatus, upon the selection of the selector elements, the selected elements are brought into engagement with their respective control members and thereafter pre-

vent movement of those members in one direction. The members so engaged by their elements are then actuated to pull upon and thereby raise the heddles connected thereto, while the remaining control members which have not been engaged by their selector elements are moved down so as to lower their corresponding heddles. In another form of the apparatus, the selector elements operate as above described, but after the control members have been selected and restrained, the heddles of the restrained members are pulled to raise their warp threads, while the heddles attached to the unrestrained control members remain in their initial positions.

For a better understanding of the invention, reference may be had to the accompanying drawings, in which

Figures 1 and 2 are vertical sectional and fragmentary top plan views, respectively, of one form of the apparatus;

Figures 3 and 4 are enlarged fragmentary vertical sectional views of parts shown in Figure 1, illustrating the parts at different stages in the operation of the apparatus;

Figure 5 is a view similar to Figure 1 of a modified form of the apparatus; and

Figure 6 is a fragmentary sectional view similar to Figure 5, but showing the parts at a different stage of the operation.

Referring now to the drawings, the apparatus is illustrated in Figure 1 in a form appropriate for use in connection with a loom, and it includes a pair of upright supporting members 10 mounted in any convenient manner, as by being attached to the side frames of the loom. Mounted in the members 10 and extending across the loom above the warp threads is a support 11 for a plurality of control members 12 provided with arms 13 and 14 lying at opposite sides of the support. The support preferably has the form of a spindle provided with a plurality of closely spaced circumferential grooves and each control member is mounted in one of the grooves and is free to swing about the spindle as an axis. The heddle 15 or group of heddles to be controlled by each control member is directly attached to the arm 13 thereof, and the arms 13 of the control members are normally supported by a bar 16 which is mounted in arms 17 of a pair of levers 18 journaled on the spindle 11 at opposite ends thereof and near the uprights 10. Each lever 18 is provided with a second arm 19 to which is connected one end of a spring 20, the other end of the spring being attached to a fixed part of the structure, such as

a cross-bar 21 extending from one support 10 to the other. The arm 19 of each lever 18 is also provided with a pin 22 straddled by the legs of a pair of forks 23, 24 at the ends of links 25, 26, respectively, these links being attached to cranks 27, 28, respectively, mounted on a rotating shaft 29 journaled in the supports 10.

Near the ends of the spindle 11, arms 30 are journaled thereon, and each of these arms has a slotted guide-way 31 in which a block 32 is movably mounted, the blocks being connected by a knife bar 33 extending across the loom. Each block 32 is connected by a link 34 to an arm 35 on the adjacent lever 18, and each arm 30 is connected by a strap 36 to a stop member 37 which is connected by a slot and pin connection 38 to the arm 19 of the adjacent lever 18. The strap 36 leading from arm 30 to stop member 37 passes about a roller 39 loosely mounted on a shaft 40 journaled in suitable bearings in the frame members 10, and the stop member 37 is provided with an abutment 37a, which normally seats against a fixed part of the frame, such as the cross-bar 21.

With the arrangement described, the rotating shaft 29 acting through the cranks 27, 28 and the links 25, 26, causes the levers 18 to be rocked in a clockwise direction about the spindle 11, the levers being restored to their original positions by the springs 20. In each clockwise movement of the levers, the arms 17 swing down, permitting the arms 13 of the control members 12 to move down with the bar 16. In such downward movement, all of the warp threads controlled by the heddles 15 would be lowered, and the selection of the warp threads to produce warp sheds is, accordingly, accomplished by restraining selected control members 12 and preventing them from taking part in the movement produced by the downward movement of the bar 16.

The selection of the control members is effected by means of a plurality of selector elements 41, one for each control member, mounted on a spindle support 42 mounted in the members 10, the spindle having circumferential channels in which are seated the selector elements, which are of relatively thin sheet material. Each selector element is provided with a hook 43 which, upon appropriate movement of its selector element, can be brought in position to engage a projection 44 on its associated control member, this projection having a face substantially radial with respect to the axis of spindle 11 and to be engaged by its hook 43 and another face 45 which lies at an angle to the radial face. The selective operation of the selector elements is accomplished by means of an electro-mechanical actuating device generally designated 46 which is mounted on a carriage 47 moved back and forth 60 across the loom on a rail 48 supported on the members 10 in any suitable way.

The actuating device 46 may take various forms, but in the construction illustrated, it includes a pivotally mounted hammer 49 which serves as, or is attached to, the armature of a pair of electro-magnets 50a, 50b attached to the carriage 47. These electro-magnets are energized and deenergized alternately under the control of a scanning mechanism, and each electro-magnet is connected through its own supply lines 51 to an amplifying device 52 connected to a source of electrical energy by lines 53. As the carriage 47 is moved back and forth across the loom, the energization of electro-magnet 50a at any particular instant causes the hammer 49 to

swing on its pivot so that one of a pair of studs 54 on the hammer engages one of the selector elements and swings it on its spindle 42 to bring its hook 43 in position in front of the projection 44 of its associated control member. The energization of electro-magnet 50b causes the hammer 49 to swing in the opposite direction and strike and swing the selector element in position to be acted on so that its hook is moved out from in front of the projection on its associated control member.

The pattern and scanning mechanism used for controlling the supply of current to the electro-magnets 50a, 50b may take various forms as, for example, the scanning mechanism may be of the photo-electric or direct contact types, such as are disclosed in the copending application of Fisher, Tandler, and Carlisle, Serial No. 92,112, filed July 23, 1936. For purposes of explanation, a scanning mechanism of the direct contact type is illustrated in the present drawings, and the pattern sheet 55 used therewith has electro-conductive and insulating areas arranged thereon in accordance with the design to be reproduced in the fabric being woven. Preferably, the pattern sheet consists of a thin metal, such as sheet copper, and the background is bare while the figures of the design are formed of insulating material, such as paint or varnish. This pattern sheet is attached at one end to a rotary support 30 56 which is rotated with a stepwise motion by means not shown during the operation of the loom. A light current is supplied to the sheet in any suitable way, as by a line 57 connected through the amplifier to the source of energy, 35 and current is withdrawn from the sheet by means of a scanning element 58 in the form of a roller mounted on a spindle 59 supported in the carriage 47, the roller being pressed yielding against the sheet by a spring 60 encircling 40 the spindle. A line 61 leading from the spindle completes the circuit.

With the arrangement described, as the carriage moves back and forth across the loom, current passes through the circuit consisting of line 45 57, sheet 55, roller 58, and roller 61 whenever the roller is in contact with an electro-conductive portion of the sheet. The connections within the amplifier are such that when the circuit through the pattern sheet is closed, amplified 50 current is supplied to the electro-magnet 50a only, energizing it and causing the hammer 49 to swing and move one or more selector elements 41 to effective position in which their hooks 43 lie in front of the projections on their associated control members. When the circuit is broken, by reason of the roller 58 resting upon an insulated area of the sheet, amplified current flows from the amplifier to electro-magnet 50b only, which then actuates the hammer and causes it to swing one or more selector elements to ineffective position in which their hooks are moved out from in front of the projections on their associated control members. In the event that the electroconductive or insulated areas on 65 the pattern sheet are of such size that one or the other of the electromagnets remains energized for a period in which the device 46 is moved past a plurality of selector elements, these elements are engaged by one or the other of the studs on 70 the hammer 49 and swung by cam action, the studs having a conical form, as shown, for this purpose.

At the beginning of the weaving operation, the selector elements are all in a position in which 75

their hooks are out from in front of the projections on their associated control members, and in the first traverse of the carriage across the loom, certain of the selector members are selected and moved to effective position with their hooks in front of the projections on their associated control members. When the carriage has completed its traverse, the levers 18 are swung clockwise by the action of cranks 25, 26 and associated parts, and move the bar 16 down. The control members, whose selector elements have not been selected, then swing clockwise with the bar and the heddles of those control members likewise move down. The control members, whose selector elements have been selected, move clockwise with the downward movement of the bar 16 to a slight extent, until their projections are engaged by the hooks on their selector elements, after which those members are restrained against further clockwise movement with the bar 16.

The clockwise movement of the levers 18 acts at once through links 34 to start the knife bar 33 moving inward toward the spindle 11, but the parts are so constructed and the operation is so timed, that the edge of the bar does not pass inward beyond the ends of arms 14 of the control members until the arms 14 of those control members which are free to move down with bar 16 have risen above the plane of movement of the knife bar. Accordingly, as the bar moves in, it passes over the tops of the arms 14 of the control members which have been selected and restrained by their selector elements, and beneath the ends of the arms 14 which have not been selected and are to move with bar 16.

As the clockwise movement of the levers 18 and bar 16 continues, the pins 38 on arms 19 of the levers reach the upper ends of the slots in the stop members 37, and thereafter the arms 30 are swung down or counter-clockwise by the straps 36 as the arms 19 move clockwise or rise. The lost motion in the connections between the arms 30 and levers 18 permits the knife bar 33 to move in over the tops of the arms 14 of the control members which are to be restrained against movement with the bar 16, before the arms 30 are moved counter-clockwise by straps 36. Accordingly, when the counter-clockwise movement of arms 30 takes place, the knife bar 33 engages the arms 14 of the control members referred to, and those members are moved counter-clockwise on spindle 11. Accordingly, when the downward movement of the bar 16 is completed, certain of the control members have been swung clockwise and the remainder counter-clockwise. The heddles have thus been segregated into two groups with one group raised and the other lowered. This completes the shed.

The shuttle or needle is now passed through the shed, and at the same time, the carriage 47 makes a return movement across the loom, during which the selection for the next shed is effected. In this selecting operation, the pattern may require that certain selector elements previously effective should be restored to ineffective position, and the elements are freely movable for that purpose since their associated control members have been swung counter-clockwise by the action of the knife bar 33. Other selector elements will then either be left in effective position or be moved to effective position by the electro-magnetic actuating device. If any elements, which are to be effective in the next operation, are associated with control members which were not previously selected and have been

moved down with the bar 16, the raising of the bar will cause those control elements to swing counter-clockwise and their projections moving beneath the hooks of their associated selector element, would tend to swing those elements to 5 ineffective position, unless such action were prevented.

To prevent the displacement of the selected elements in the manner described, there is provided a spring plate 62 extending across the loom 10 and carried by suitable supports 63 movably mounted in guide-ways in the members 10. Each support 63 is connected by a link 64 to an arm 65 fast on a shaft 66 mounted in the members 10 and provided with an arm 67 carrying a roller 15 67a bearing on a cam 68 fast on shaft 40. The cam action is so timed that, after the carriage 47 has moved across the loom and completed its selecting operation, the spring plate 62 is advanced toward the spindle 42. The plate is provided with spring teeth 62a, one for each selector element, and in the advance of the plate, these teeth pass beneath the ends of arms 41a on those elements which have been moved to effective position in the selecting operation. 20 Thereafter, as the bar 16 raises the previously unselected control members and the projections on those members pass beneath the hooks of their associated selector elements, such of the elements as have been moved to effective position are raised by the projections, and this causes the arms 41a of such elements to move down against the spring fingers 62a. When the projections have passed behind the hooks, the spring fingers raise the arms 41a and this restores the 35 selected elements to effective position.

As the levers 18 and bar 16 start to return to their initial positions, the pins 38 move lengthwise in the slots in the stop members 37, and the arms 30 are given an initial clockwise movement 40 by the weight of their heddles and warp threads, to take up the lost motion in the connections. Thereafter, as the levers 18 swing counter-clockwise, the arms 30 swing clockwise at the same rate, and the knife bar 33 moves outwardly along 45 the tops of the arms 14 of the control members. Just as the knife bar is freed from the tops of the arms 14, the arms 13 of the associated control members are engaged by the bar 16 and all the control members then remain in their common 50 initial position until the bar 16 moves down again.

In the modified form illustrated in Figures 5 and 6, the apparatus includes control members 12 mounted on a spindle 11 and selectively restrained by selector elements 41 actuated by an electro-mechanical device 46 mounted on a carriage 47 carrying the direct contact scanning element 58, these parts being of the construction previously described. The arms 13 of the control elements 60 are directly connected to heddles 15 which pass over guide rods 69 and thence extend downward to the warp threads. Mounted on the spindle 11 at the opposite ends thereof are bell crank levers 70 connected by a bar 71 having a row of openings through which pass the individual heddles 15. These bell cranks 70 are raised and lowered by links 72 actuated by suitable means not shown, such as cams, and each bell crank lever 70 has one arm 73 connected by a link 74 to a block 75 70 mounted for sliding movement in guide-ways 76 in one of the frame members 10, the blocks 75 supporting a knife bar 77.

With the construction described, at the completion of each selecting operation by the movement 75

of the carriage across the loom, certain of the selector elements 41 will have been moved to effective position in which their hooks 43 lie in front of projections 44 on their associated control members. The levers 70 are now moved down, and in this movement, those control members which have not been selected and held by their associated selector elements will likewise move down. The downward movement of any control member has no effect on its heddle, since that portion of the heddle between the control member and the guide rod 69 simply swings about the rod as a center without raising or lowering the heddle eye to any substantial extent. The downward movement of the bar 71, however, causes a pull on the heddles 15 of those control members which have been restrained by their associated selector elements, and this pull is sufficient to raise the heddles so that a warp shed is thereby produced.

As the shuttle or needle passes through the shed, the selector elements must be set up for the next shedding operation, and this necessitates that all the selector elements including those which have been effective, should be freely movable. The knife bar 77 is provided for this purpose, and as the levers 70 move down, the bar is moved in over the arms 14 of the control members 13 which have been restrained by their selector elements. The shape of the under surface of the bar is such that in its inward movement, it forces the arms 14 downward to a slight extent and thereby moves the previously restrained control members clockwise to an amount sufficient to release the hooks of their associated selector elements. These elements may then be actuated by the electro-magnetically operated hammer in the manner previously described. As the levers 70 rise, the knife bar 77 is moved out from above the arms 14 and frees these arms just as the bar 77 engages the arms 13 of the respective control members. The parts are thereupon in their initial positions and the cycle of operations is repeated.

In both forms of the apparatus described, it will be noted that the heddles of the control members which are selected and restrained by the action of their selector elements are raised so that their warp threads are moved into the upper part of the shed, and the warp threads controlled by heddles whose control members have not been selected remain in the lower part of the shed. In the construction illustrated in Figure 1, the two groups of warp threads segregated by the selecting operation are moved in opposite directions from their initial level position, while with the construction shown in Figures 5 and 6, only the warp threads which are to lie in the upper part of the shed are moved, and the remainder stay in their level position. The new apparatus thus takes the place of a Jacquard mechanism and eliminates the use both of a set of punched cards and of the card barrel, needles, hooked wires, and lifting apparatus of such a mechanism. The pattern sheet employed with the new control carries a representation of the design which is to be reproduced, and since such a sheet can be made at much less cost than the set of cards which would be necessary with a Jacquard mechanism to reproduce the pattern, the use of the new apparatus reduces the cost not only of the equipment, but also of operation in the weaving of figured fabrics.

We claim:

75 1. In a pattern control mechanism for con-

trolling the operation of the heddles of a loom, the combination of a plurality of control members connected directly to the heddles to be controlled thereby, means for actuating the control members selectively to cause the heddles of selected members to be displaced to form a warp shed, and means for selecting the control members including a plurality of selector elements, one for each control member, means for operating selected elements to render them effective to prevent movement of their respective members in one direction, and separate means for engaging and holding said respective members against movement in said direction.

2. In a pattern control mechanism for controlling the operation of the heddles of a loom, the combination of a plurality of control members connected directly to the heddles to be controlled thereby, means for actuating the control members selectively to cause the heddles of selected members to be displaced to form a warp shed, and means for selecting the control members including a series of selector elements, one for each control member, means for operating selected elements to render them effective to prevent movement of their respective members in one direction, including an actuating device and means for causing a relative movement of the device and the series of selector elements, and separate means for engaging said respective members and preventing movement thereof in said direction.

3. In a pattern control mechanism for controlling the operation of the heddles of a loom, the combination of a plurality of control members connected directly to the heddles to be controlled thereby, means for actuating the control members selectively to cause the heddles of selected members to be displaced to form a warp shed, means for selecting the control members including a series of selector elements, one for each control member, means for operating selected elements to render them effective to prevent movement of their respective members in one direction, including an electro-mechanical actuating device and means for moving said device along the series of selector elements, and separate means for engaging said respective members and preventing movement thereof in said direction.

4. In a pattern control mechanism for controlling the operation of the heddles of a loom, the combination of a plurality of control members connected directly to the heddles to be controlled thereby, means for moving the control members between two positions, a plurality of selector elements, one for each control member, means for operating said elements selectively to cause them to restrain their associated control members against being thus moved by said moving means, and means for moving said restrained control members between one of said positions and a third position.

5. In a pattern control mechanism, the combination of control members connected directly to the parts to be controlled thereby, means normally operating to cause a reciprocating movement of all said control members along one path, means for selecting the control members to receive such movement including selector elements, one for each member, said elements being operable to restrain their respective members against said movement, and means under the control of a pattern for actuating the elements selectively, and means for giving the restrained control mem-

bers a reciprocating movement along another path.

6. In a pattern control mechanism, the combination of control members connected directly to the parts to be controlled thereby, means for moving the members selectively to secondary positions displaced from a common initial position of said members, including a support for the members movable to and from one of said secondary positions, and means engageable with the members to move them to and from the other of said secondary positions, and means for controlling the operation of the moving means, including a pattern, a plurality of selector elements, one for each control member, movable to engage and restrain their respective members against movement to one of said secondary positions, and means under the control of the pattern for operating the elements selectively.

7. In a loom, the combination of heddles, control members connected to the heddles to be controlled thereby, and means for moving the control members selectively to secondary positions displaced from a common initial position to produce warp sheds, said means including a member movable with the control members to and from one of said secondary positions, a plurality of selector elements, one for each control member, movable selectively to engage their respective members and hold them against movement with the movable member, means under the control of a pattern for operating the elements selectively, and means for moving control members not held by their respective selector elements to and from the other of said secondary positions.

8. In a loom, the combination of heddles, control members connected to the heddles to be controlled thereby, and means for moving the control members selectively to secondary positions displaced from a common initial position to produce warp sheds, said means including an abutment member movable with the control members to and from one of said secondary positions, a plurality of selector elements, one for each control member, movable selectively to engage their respective members and hold them against movement with said abutment member, means under the control of a pattern for operating the elements selectively, and means connected to said member and operable therewith for moving control members not held by their respective selector elements to and from the other of said secondary positions.

9. In a loom, the combination of heddles, control members connected to the heddles to be controlled thereby, and means for moving the control members selectively to secondary positions displaced from a common initial position to produce warp sheds, said means including a support for said members movable with the members thereon to and from one of said secondary positions, a plurality of selector elements one for each control member movable selectively to engage their respective members and restrain them against movement with the support, means under the control of a pattern for operating the elements selectively, and means for moving control members not restrained by their respective selector elements to and from the other of said secondary positions.

10. In a loom, the combination of heddles, control members connected to the heddles to be controlled thereby, and means for moving the control members selectively to secondary positions displaced from a common initial position

to produce warp sheds, said means including a support for said members movable with the members thereon to and from one of said secondary positions, a plurality of selector elements, one for each control member, movable selectively to engage their respective members and restrain them against movement with the support, means under the control of a pattern for operating the elements selectively, and a bar connected to and movable with said support for moving control members not restrained by their respective selector elements to and from the other of said secondary positions.

11. In a pattern control mechanism for controlling the operation of the heddles of a loom, the combination of a plurality of control members connected to the heddles to be controlled thereby, means for operating the control members selectively and causing selected heddles to be displaced to form a warp shed, and means for selecting the control members including a plurality of selector elements, one for each control member, engageable with their respective control members to restrain them against movement in one direction, a device movable relative to the selector elements and operable under the control of a pattern for actuating said elements to cause them to perform their restraining function, and means for engaging actuated elements and holding them in position after such actuation.

12. In a pattern control mechanism, the combination of a plurality of control members, means for moving said members to and from an initial position, and means for selecting the members to be moved by said moving means, said selecting means including a plurality of selector elements, one for each control member, engageable with their respective control members for restraining the latter against movement in one direction, means under the control of a pattern for selectively operating said selector elements to cause them to perform their restraining function, and a member movable into engagement with said selected and operated elements and preventing displacement thereof by said control members during the movement of the latter.

13. In a pattern control mechanism, the combination of a plurality of control members mounted for swinging movement, each member having a pair of arms, means engageable with one arm of each control member and operable to cause movement of said members to and from a secondary position displaced from the common initial position of said members, means for selecting the control members to be moved by said moving means and including a plurality of selector elements, one for each control member, engageable with their respective control members for restraining them against movement to said secondary position, means for operating said selector elements selectively, and means engageable with the other arms of said control members and operable to move the control members unrestrained by their selector elements to another secondary position.

14. In a pattern control mechanism for controlling the heddles of a loom, the combination of a plurality of freely movable control members connected directly to the heddles to be controlled thereby, a plurality of selector elements one for each member, means operable to impart a movement to all the control members in unison, means for operating the elements selectively to restrain their associated members from being moved by

the operation of said moving means, and means independent of said elements for engaging the restrained members and preventing them from being moved by said moving means.

- 5 15. In a pattern control mechanism for controlling the heddles of a loom, the combination of a plurality of control members mounted for movement and connected directly to the heddles to be controlled thereby, a plurality of selector elements, one for each member, operable to restrain their respective members against movement, means for operating the elements selectively, means for moving the unrestrained control members, and a second means for engaging and restraining the control members previously restrained by said selector elements.

- 10 16. A pattern control mechanism which comprises, a plurality of movable control members connected respectively to the parts to be controlled thereby, a plurality of selector elements, one for each member, operable to engage and restrain their associated members, means for moving the unrestrained control members, means engaging the control members restrained by said selector elements and moving them to release said elements, and means under the control of a pattern for operating the selector elements selectively.

17. A pattern control mechanism which comprises, the combination of a plurality of control members connected respectively to the parts to be controlled thereby, a plurality of selector elements one for each member operable to engage and restrain their associated members, means for moving the unrestrained control members, means for engaging the restrained control members and moving them to release the selector elements therefrom, means under the control of a pattern for operating the selector elements selectively, and means engageable with selected elements for holding them in actuated position. 5 19

18. In a pattern control mechanism, the combination of a plurality of control members, means for moving the control members in unison between two positions, a plurality of selector elements, one for each control member, said elements being engageable with their respective control members to restrain the latter against movement by said moving means, means for operating said selector elements selectively to cause them to perform their restraining function, and means engaging the selector elements so operated and holding them in restraining position. 20 25
